UNITED STATES PATENT OFFICE.

JOSEPH RANGETTE, OF DÜSSELDORF, GERMANY.

DESIGN FOR A BOOK-COVER.

SPECIFICATION forming part of Design No. 20,292, dated November 11, 1890.

Application filed October 9, 1890. Serial No. 367,595. Term of patent 7 years.

To all whom it may concern:

Be it known that I, JOSEPH RANGETTE, a subject of the German Emperor, residing at Düsseldorf, in Germany, have invented and produced a new and original Design for Book-Covers, of which the following is a specification, reference being had to the accompanying drawings, forming part thereof.

Figure 1 is a face view of a book-cover showing my design. Fig. 2 shows the cover rolled up.

The leading feature of my design consists in a book-cover presenting an appearance of having rested upon the bottom of the sea for 15 a long time.

A represents a book-cover provided with ornaments consisting of shells *a*, twigs *b*, pebbles *c*, and sand *d*.

e is an old English title, and *f* a seal, with which the cover is ornamented.

What I claim is—

The design for a book-cover, substantially as shown.

In testimony whereof I have signed this specification in the presence of two subscribing witnesses.

JOSEPH RANGETTE.
